(57) CLAIM

The ornamental design for a hair tools travel bag, as shown and described.

DESCRIPTION

FIG. 1 is a front, right, top perspective view of a hair tools travel bag, showing my new design;

FIG. 2 is a rear, left, bottom perspective view thereof;

FIG. 3 is a front elevational view thereof;

FIG. 4 is a rear elevational view thereof;

FIG. 5 is a left side view of the enlarged scale thereof;

FIG. 6 is a right side view of the enlarged scale thereof;

FIG. 7 is a top plan view thereof; and,

FIG. 8 is a bottom plan view thereof.

The dashed broken lines in the figures are for the purposes of illustrating portions of the hair tools travel bag that form no part of the claimed design.

1 Claim, 8 Drawing Sheets
